UNITED STATES PATENT OFFICE.

WILLIAM A. REDDING, OF MACON, GEORGIA.

ORE-SEPARATOR.

SPECIFICATION forming part of Letters Patent No. 668,742, dated February 26, 1901.

Application filed August 6, 1900. Serial No. 26,107. (No model.)

To all whom it may concern:

Be it known that I, WILLIAM A. REDDING, a citizen of the United States, residing at Ma-
5 con, in the county of Bibb and State of Georgia,
have invented certain Improvements in Ore-
Separators, of which the following is a speci-
fication.

This invention relates particularly to sep-
arating graphite from other material with
10 which it occurs, and in the separation advan-
tage is taken of the fact that the graphite is
of lower specific gravity than the other ma-
terials, that it is found in laminae or scales,
and that it will readily float, owing to its re-
15 pelling water.

In the accompanying drawings, Figure 1 is
a perspective view showing all that portion of
my apparatus which contains novelty herein
claimed. Fig. 2 is a section through the line
20 2 2, Fig. 1. Fig. 3 is a plan of a certain air-
chamber.

The object of the invention is to produce a
very simple and inexpensive apparatus that
shall separate minerals perfectly without
25 waste and with great rapidity.

Wherever the letters occur in the drawings,
A designates a suitable frame, of wood or
other material, supporting a structure, pref-
erably of sheet metal, made up of a water-
30 compartment B, a downwardly-convergent
upwardly-open vessel C, having at its apex a
valve-controlled discharge, and an overflow-
trough D, leading from said vessel, the com-
partment, vessel, and trough being preferably
35 of equal width. The compartment B is a
closed box supplied with water through a
valved pipe E and having its inclined wall B'
perforated, so that water entering it through
the pipe may be discharged through these per-
40 forations. Above the rear end of the frame,
which is the left-hand end in the drawings, is
a V-shaped inclined hopper F, which may be
supported in any suitable manner and which
is provided with a preferably-valved aperture
45 F' for discharging material in the medial ver-
tical plane of the structure below. The ma-
terial in falling strikes upon the upper part
of a half-cone G, fixed upon an adjustably-
inclined plate H, supported from the frame A,
50 both cone and plate terminating a little above
the plane of the vessel C and a little in front
of the compartment B. Below the plate and

cone is a hollow closed wedge-shaped cham-
ber I, having its thin front edge parallel to
the plane of the trough and provided with 55
forwardly-directed perforations. This cham-
ber is adjustably mounted, so that it may be
inclined downwardly forward at such angle
as may be desired, and it is supplied with air
more or less compressed and entering through 60
a flexible pipe J, provided with a controlling
device or valve J'.

When the apparatus is to be used, the valve
in the pipe E is opened, admitting water to
the compartment B, whence it passes into 65
and fills the vessel C and overflows along the
trough D, the discharge at the apex of the
vessel being closed or so adjusted as to dis-
charge only a fraction of the entering water.
The supply of water entering through the 70
pipe E is so adjusted that a thin stratum of
overflowing water shall cover the bottom of
the trough and advance with but moderate
velocity. The valve J' is opened, allowing
small jets of air to escape, either horizontally 75
or at a slight downward angle toward the
trough and above the path of the water es-
caping from the compartment B. The mate-
rial to be separated is then allowed to drop
from the hopper upon the cone G, down which 80
it passes, spreading out and leaving the base
of the cone in a very thin curved sheet. As it
leaves the cone every part of this sheet is
struck by the forwardly-moving air issuing
from the wedge-like chamber. By this spread- 85
ing out the material and subjecting it to the
air-blast practically every particle of graph-
ite is separated from its fellows, so that few
granules of extraneous material are held or
protected by the graphite, and as the graph- 90
ite is both lighter than the other components
and of flake-like form, presenting to the air
more surface than an equal amount of the
other material, it is all blown forward farther
than the latter and drops gently upon the 95
surface of the slowly-moving unruffled water,
while the heavier and more rounded particles
of extraneous matter, being comparatively
little deflected by the air, drop through the
water-spray from the water-compartment, 100
which breaks loose the comparatively few
positively adherent particles of graphite.
Thus practically completely freed from the
graphite the heavy particles sink quickly

and pass out at the apex of the vessel, either continuously with a small amount of water or by opening the valve at intervals. While, as has been suggested, some flakes of graphite 5 may adhere to heavy granules of rock, on the other hand some small particles of rock adhere to flakes of graphite and fall upon the surface of the water with them; but as the layer of graphite upon the water is quite thin, 10 and as such particles readily become wet while the graphite does not, they are almost without exception detached in time to sink upon the front wall of the vessel and slide down to join the mass being discharged at 15 the vessel's apex. The apparatus being once properly adjusted to the grade of material operated upon is automatic in its action, practically pure graphite being continually discharged through the trough and material containing 20 practically no graphite passing out from the apex of the vessel C.

What I claim is—

1. In an ore-separator, the combination with a body of water and means for giving its surface stratum lateral motion, of means for discharging above the plane of the surface material to be separated, and means for directing upon the falling material an air-current approximately parallel to said stratum. 25
2. In an ore-separator, the combination of a body of water, of means for discharging water in a spray upon one side of said body, means for discharging above such spray material to be separated, and means of directing 30 an air-current upon the falling material, 35

above the spray, to blow its lighter components upon the water beyond the latter.

3. The combination with a body of water and means for giving its surface stratum a lateral traveling motion, of means for discharging above said body material to be separated, means for directing upon the falling material a transverse air-blast, and means for at will varying the angle of said air-blast. 40

4. The combination with a body of water and means for giving its surface stratum a lateral traveling movement, of means for discharging above said body material to be separated, a cone-like device interposed in the path of the falling material, an angularly-adjustable air-blast device discharging between the cone and the water and means for adjusting the inclination of the cone's axis. 45

5. The combination with the downwardly-convergent water vessel, having at one side an overflow-trough, of the perforated water-compartment at the opposite side of the vessel and above the level of the overflow, a valved pipe supplying water to said compartment, means for discharging material, to be separated, above and near the perforated side of said compartment and means for producing an air-current between the discharge-point and the compartment and in the direction of said trough. 50
